BY B. C. Stickney

ATTORNEY.

UNITED STATES PATENT OFFICE.

EDWIN A. PETERSON, OF MADISON, WISCONSIN, ASSIGNOR TO UNDERWOOD TYPE-WRITER COMPANY, OF NEW YORK, N. Y., A CORPORATION OF DELAWARE.

TYPEWRITING-MACHINE.

1,397,544.

Specification of Letters Patent.

Patented Nov. 22, 1921.

Application filed March 2, 1920. Serial No. 362,644.

To all whom it may concern:

Be it known that I, EDWIN A. PETERSON, a citizen of the United States, residing in Madison, in the county of Dane and State 5 of Wisconsin, have invented certain new and useful Improvements in Typewriting-Machines, of which the following is a specification.

This invention relates to typewriters, and, 10 more particularly, to means adapted to facilitate the erasure of matter erroneously typed on a work-sheet without shifting such matter from the printing line.

Heretofore, it has been the practice in 15 typewriters having long alining devices extending along the printing line, in case of an error which necessitates the erasure of one or more characters, to first rotate the platen to advance the work-sheet and thus move the 20 part bearing the characters to be erased to a position sufficiently removed from the type-bar guide and ribbon mechanism to permit the erasure to be effected. In many cases, after making an erasure, in the above- 25 mentioned manner, the operator has failed either to bring the line in which the error was made back exactly to the printing line or to return the sheet at all. In either of these cases, the characters typed to correct 30 the error would be out of alinement and such characters might be slightly displaced laterally, thus detracting from the desired uniformity and neatness of the typed page.

The foregoing objectionable features have 35 been satisfactorily overcome by the herein-disclosed invention which comprises an improved work-sheet alining gage or wing scale having a cut-away portion or recess in its alining edge at a point which will be 40 readily accessible to the typist, so that whenever an error is made, the same may be corrected by merely moving the typewriter carriage laterally, so as to bring the incorrectly 45 typed characters in register with the recessed portion in said gage or scale, after which the erasure may readily be made. In order that errors may be corrected at any 50 point in a typed line, two such gages or scales may be employed, one at each side of the printing point of the machine.

It may be observed that the improved gage or wing scale renders it unnecessary to rotate the platen or to otherwise change the line-spacing relation of the work-sheet relatively 55 to the printing mechanism before making an erasure. It therefore entirely eliminates

the possibility of varying the adjustment of the work-sheet relatively to the printing mechanism and renders readjustment unnecessary, thereby resulting in economy of 60 time and labor as well as contributing materially to the neatness and general appearance of the work which may be executed by the machine.

The herein-disclosed invention has an 65 added advantage when it is desired to correct an error made near the bottom of a work-sheet. Heretofore, it has been impossible to correct such an error without removing the sheet from the machine, since 70 the necessary rotation of the platen to advance the same to a sufficient extent, to permit the erroneous characters to be erased, would cause its trailing end to be advanced beyond the feed-rolls. When making a cor- 75 rection on a work-sheet being typed on a machine having my invention applied thereto, the erasure may be as readily made in the last line typed upon the sheet as at any other point, since the letters to be erased may be 80 brought to a position adapted for such purpose by merely letter-spacing or back-spacing the carriage, as above explained, without line-spacing the same.

Other features and advantages will here- 85 inaftter appear.

In the accompanying drawings,

Figure 1 is a top or plan view of a part of an Underwood standard typewriter with my invention applied thereto.

Fig. 2 is a detail of one form of the im- 90 proved sheet-alining gage or wing scale.

Referring to the above-mentioned drawing, 10 represents the usual platen and 12 the type-bar segment of a typewriter. At 95 14 is indicated the usual type-bar guide, which may be secured to the type-bar segment in any appropriate manner. The usual ribbon vibrator, for bringing the ribbon 16 to the printing line at each depression of a 100 key, is indicated at 17, said ribbon being fed from one to the other of ribbon spools 18 in the usual manner.

At 24 is represented my improved sheet-alining gage or wing scale, which may be 105 pivoted, as by means of a pin 25, to a bracket 26, secured by screws or other appropriate fastening means 27 to the type-bar segment. One such gage or wing scale may be mounted at each side of the type-bar guide 110 and ribbon vibrator. Each of these gages or wing scales may be yieldingly held in

close relation with a work-sheet, when placed about the platen, as by a spring 28, coiled about the pin 25, mounted in the bracket 26, and having one end 29 bearing against the 5 wing scale, and the other end 30 bearing against said bracket. The position of the wing scale relatively to the platen is determined by a stop 31 adapted to be brought into contact with the upper surface of the 10 type-bar segment. The upper edge 32 of each wing scale is so positioned relatively to the platen, and to the point at which the type-bars are brought to printing position, as to immediately underlie the characters 15 typed upon a work-sheet. The edge 32 of each gage or scale may also be provided with letter-space indications 33 in the usual manner.

The alining gage or wing scale herein 20 disclosed is a modification of one now in use on the Underwood typewriter and differs therefrom in the following particulars:

Midway between the ends of the gage or 25 wing scale 24, there is provided a cut-away portion or recess 34 providing ample space through which access may be had to an underlying work-sheet when it is desired to make an erasure of characters erroneously typed thereon. The outline of the wing 30 scale is also modified, as indicated in Fig. 2, in which the dot-and-dash lines indicate that of the gage or scale now in use on the Underwood typewriter. It may be observed 35 that the gage has been enlarged or increased in dimensions at the lower right-hand side, as indicated at 35, so that it will not be unduly weakened as a result of the cutting away of part of the material to form the recess 34, and that additional metal has also 40 been added at the left end of the gage or scale, as indicated at 36, Fig. 2, so as to provide a letter-space scale of ample length, the letter-positioning notch 37 being located at the extreme left end in the added portion, 45 as illustrated in Fig. 2.

As already explained, the positions of the alining gages or wing scales are such that the last line of characters typed upon a work-sheet will always lie immediately above 50 the edges 32 of said gages. Should one or more characters be erroneously typed upon the sheet, it is impossible to erase them without first making some change in the position of the sheet relative to the printing 55 mechanism because of the proximity of the ribbon vibrator and type-bar guide. All that is necessary, however, is to letter-space or back-space the carriage laterally, so as to bring the erroneously typed characters 60 in register with one of the recesses or notches 34 in the gage or wing scale, after which the erasure may readily be made. It may be observed, on reference to Fig. 1, that these 65 notches are located at points so related to the positions of the ribbon spools and the

ribbon as to afford most convenient access to the operator when making an erasure.

It will be apparent, from the foregoing description, that the improved gage or wing scale provides means for making erasures of erroneously typed letters, numbers or other characters without in any manner disturbing the adjustment between the platen and the work-sheet, thus avoiding the necessity for making readjustments and the attendant possibility that such readjustments might not be accurately made, in which case the typed sheet would be lacking in uniformity and neatness. It will also now be apparent that the herein-disclosed invention 70 provides means for making erasures of letters erroneously typed at the bottom of the work-sheet, which could not otherwise be corrected without removing the work from the machine.

Variations may be resorted to within the scope of the invention, and portions of the improvements may be used without others.

Having thus described my invention, I claim:

1. A wing-scale for a typewriting machine, having a long alining edge to lie along the platen at the printing line and at one side of the printing point, and an erasure opening in said wing-scale at said alining edge to enable the erasure of erroneously-typed characters in the printing line when said characters are brought opposite the erasure opening by longitudinal shifting of the platen.

2. A work-sheet-alining gage for a typewriter, having a long alining edge to maintain work-sheets against the platen at the printing line, and an erasure opening in said edge to enable the erasure of erroneously-typed characters at the printing line when at the erasure opening.

3. In a typewriting machine, a device comprising two work-sheet-alining gages supported on the typewriter frame and having long upper alining edges lying immediately below the printing line and extending from the printing point on opposite sides thereof, said gages also serving to hold a work-sheet in proper relation to the platen along the printing line, each of said gages having an erasure recess in its alining edge, so that any portion of the work-sheet along the writing line may, by longitudinal shifting of the platen, be brought into register with one or the other of said recesses to permit erasure of erroneously-typed characters without shifting the work-sheet to move the erroneously-typed characters away from the printing line.

EDWIN A. PETERSON.
